OR D12,590 EX

DESIGN FOR STATUARY.

Design No. 12,590, dated December 6, 1881.

UNITED STATES PATENT OFFICE.

JOHN ROGERS, OF NEW CANAAN, CONNECTICUT.

DESIGN FOR STATUARY.

SPECIFICATION forming part of Design No. 12,590, dated December 6, 1881.

Application filed October 22, 1881. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying drawings, forming part thereof.

10 The group consists of a man and boy on a horse, and is called "Fetching the Doctor." The boy is sitting in front, bareheaded and with bare feet, and is driving the horse, which is going on a fast trot.

the boy and holding onto him by his right hand, and with the other holding his hat on his head, while the wind blows his coat-tails out behind.

I claim—

The design for a group of statuary herein shown and described, consisting of a man and boy riding a horse, which is going on a fast trot.

JOHN ROGERS.
